TUBE CAP

Application filed July 9, 1932. Serial No. 621,723.

The invention relates to receptacle caps, particularly of the type shown and described in my application, Serial #577,814, filed November 28, 1931, and has for its object to provide means whereby the cap discharge port may be formed when the cap is initially screwed to closed position on the tube neck.

A further object is to provide a cap having the discharge port partially formed therein during the molding operation, thereby providing a weakened portion, which portion, when the cap is initially screwed to closed position on a tube neck, is broken out by the conical faced valve stem carried by the neck, thereby preventing the forming of a burr when it is attempted to mold the discharge port at the time of molding the cap.

A further object is to mold the cap port whereby the weakened portion left in the port is thicker centrally than at its sides, thereby insuring a positive breaking around the port edges, free of burrs.

A further object is to provide a molded receptacle cap with a partially formed discharge port, thereby providing a weakened wall across the discharge port, positioned where upon screwing the cap to closed position on a discharge neck, said weakened portion will be punched out by a conical faced valve stem carried by the neck, thereby completing the formation of the discharge port in the cap and obviating the necessity of removing burrs from the cap, which form when an attempt is made to completely mold the discharge port in the cap.

A further object is to provide an expandable split ring in a channel of the receptacle neck and in a channel in the inner periphery of the cap, said ring having vertical play on the neck when the cap is screwed to closed position as well as to open, but cooperating with shoulders of the channels, thereby locking the cap on the neck and allowing limited axial movement thereof.

With the above and other objects in view the invention resides in the combination and arrangement of parts as hereinafter set forth, shown in the drawing, described and

claimed, it being understood that changes in the precise embodiment of the invention may be made within the scope of what is claimed without departing from the spirit of the invention.

In the drawing:

Figure 1 is a vertical transverse sectional view through the cap, and a portion of the neck, showing the cap in position to be screwed onto the neck.

Figure 2 is a view similar to Figure 1, but showing the cap at an intermediate closed position during the port forming operation.

Figure 3 is a vertical transverse sectional view through the cap and neck, showing the cap in closed position and the port formed.

Figure 4 is a vertical transverse sectional view through the cap, showing the same on an enlarged scale.

Figure 5 is a vertical transverse sectional view through the cap on an enlarged scale showing the breaking out operation and more clearly the relatively thin connection between the break out disc and the body of the cap.

Referring to the drawing, the numeral 1 designates the neck of a receptacle, for instance a collapsible tube, and 2 the cap of the general type, for instance as shown and described in my application above identified. Extending upwardly from the discharge neck of the tube is a conical faced valve stem 3, which is adapted to seat in the tapered discharge port 4.

It has been found that where an attempt is made to mold the caps from plastic material and also the port 4 therein, a burr is formed around the edge 5 of the port, which has to be removed at considerable cost. In the present device, however, such a burr is not formed. When the cap 2 is molded, it is molded with a weakened disc portion 6 at the outer end of the discharge port 4 and when the caps are screwed onto the necks of receptacles, the conical faced valve stems 3 engage the weakened portions 6, forcing and breaking out the same. When the caps are molded, the discs 6 are molded with a relatively thin connection at 7 to the cap, and as the material is brittle, it will

be seen that there will be a clean break, free of burrs. By having the central portions of the discs 6 thicker, it is obvious the breaking will be at 7.

5 It will be noted that when tubes are filled, they are filled with the caps in closed position on the necks 1, through the bottoms of the tubes, which are afterwards sealed. Under these conditions, the breaking out 10 of the frangible disc 6 is accomplished in the usual operation by placing the cap on the tube neck, thereby utilizing this operation for the valve port formation, and obviating any extra handling or operation.

15 The upper end of the neck 1 is preferably provided with a ductile or pliable flange 9, which engages the arcuate shoulder 9 and is deformed so as to conform to the arcuate shoulder when the cap is in closed position, thereby forming a positive seal between the cap and the threaded connection 10 for preventing leakage of material through the thread, particularly when the tubes are subjected to pressure during shipment.

20 25 It has been found desirable to provide, in connection with caps of this character, captive means for preventing the cap from being entirely unscrewed from the threaded neck 1, and to accomplish this result, a split ring 11 is provided which is initially placed over the end of the neck 1 and in the relatively wide channel 12 of the neck. When the cap is then screwed on the neck, as shown in Figure 1, the annular bead 13 within the 30 35 cap engages the ring 11 and contracts the same as clearly shown in Figure 2, then upon continued movement of the cap toward closed position, the split ring 11 is received within the channel 14 in the inner periphery of the cap, thereby positioning the ring in registering channels 12 and 14 where it will cooperate with the shoulders of the channels for limiting the outer movement of the cap for preventing removal of the cap and consequent loss of the same. The amount of movement is regulated by the width of the channels 12 and 14.

40 45 50 From the above it will be seen that a cap for receptacles is provided whereby a discharge port is partially molded within the cap and the discharge port is then formed by a breaking out method when the cap is screwed on the receptacle neck, thereby reducing the labor cost to a minimum and at 55 the same time overcoming the difficulty of burrs forming around the outer periphery of the ports when the port is entirely molded during the molding of the cap. When an attempt is made to mold the cap with a completed port, it has been found that a thin film of material is forced into the clearance between the male and female mold elements, as the material from which the caps are 60 65 molded is in a powdered or plastic form and is melted as the molds are brought to-

gether. This thin film of material rapidly solidifies and forms the burr referred to.

The invention having been set forth what is claimed as new and useful is:—

1. The combination with a receptacle 70 neck, a cap axially movable on said neck, a valve stem carried by said neck, of a partially formed valve seat and port in said cap for said valve stem, said valve seat and port being closed by a frangible disc formed integral with the cap. 75

2. The combination with a tube cap threaded on a tube neck and movable axially towards and away from a valve stem carried by the neck, of a partially formed valve 80 seat in said cap in axial alignment with the valve stem, said valve seat being closed by a frangible wall formed integral with the cap.

3. The combination with a tube cap 85 threaded on a tube neck, a valve stem carried by said neck and extending upwardly therefrom, of a cap port partially formed in alignment with the valve stem and adapted to be completed by the valve stem 90 upon movement of the cap to closed position.

4. The combination with a receptacle 95 neck, a cap mounted on said neck and axially movable in relation thereto, a valve stem carried by said neck, of a partially formed valve seat for said valve stem in said cap and normally sealed by a relatively thin wall.

5. The combination with a receptacle 100 neck, a cap mounted on said neck and axially movable in relation thereto, a valve stem carried by said neck, of a partially formed valve seat in said cap for receiving said 105 valve stem, said valve seat being normally sealed at one end by a relatively thin wall and positioned whereby upon movement of the cap to closed position on said neck, said thin wall will be punched from the valve seat by the valve stem, thereby completing 110 the formation of the valve seat and a discharge port.

6. A device as set forth in claim 5 wherein the valve seat disc is thicker centrally than around its sides. 115

7. A device as set forth in claim 5 wherein the disc normally sealing the discharge port and valve seat is relatively thin around its sides.

8. As an article of manufacture, a tube 120 cap formed from frangible material and having formed therewith a partially formed valve seat and discharge port closed by a relatively thin wall.

9. The combination with a cap threaded 125 on a tube neck, a channel in the outer periphery of the neck, a split ring in said channel, an annular rib carried by the cap on its inner periphery and adapted to compress said split ring sufficient for the an- 130

nular rib to pass said ring when the cap is screwed to closed position, a channel in the inner periphery of the cap, said split ring being expansible and adapted to expand 5 back into said channel in the inner periphery of the cap above the rib, said split ring cooperating with shoulders formed by said channels whereby the outer movement of the cap to an open position is limited.

10 In testimony whereof he hereunto affixes his signature.
